MUSICAL INSTRUMENT

**Lloyd A. Loar, Kalamazoo, Mich., assignor, by
mesne assignments, to Acousti-Lectric Com-
pany, Kalamazoo, Mich., a corporation of
Michigan**

Application January 27, 1934, Serial No. 708,570

10 Claims. (Cl. 84—1)

My invention relates to musical instruments and more particularly to such instruments of the keyboard or clavier type having electrical amplifying means associated therewith.

5 The main objects of my invention are:

First, to provide a musical instrument of this character which is generally more refined, simpler and in some respects an improvement over the musical instrument disclosed in my copending application, Serial No. 708,568, filed concurrently herewith.

10 Second, to provide an improved mounting for the tuned reeds so that both ends thereof are free to vibrate, one end being used to initiate the vibration and the other end being used as an armature.

15 Third, to mount the reeds so as to produce a vibrato by permitting both ends to vibrate and means for selectively controlling the vibration of one or both of such ends.

20 Fourth, to provide a musical instrument having reeds mounted in this manner and vibrated so that the resultant tone is free of mechanical interference.

25 Fifth, to provide an improved mechanical movement or action for picking the reeds to initiate the vibration thereof.

Sixth, to provide means affording ready access to the pick-ups through the back of the 30 instrument.

Seventh, to provide a musical instrument having the above desirable features and advantages and which is simple and economical in its parts and very efficient and effective in operation.

35 Objects relating to details and economies of my invention will appear from the description to follow. The invention is defined and pointed out in the claims.

40 A structure which is a preferred embodiment of my invention is illustrated in the accompanying drawings, in which:

Fig. 1 is a rear perspective view of a musical instrument embodying the features of my invention, the back panel being shown in open 45 position in dotted outline.

Fig. 2 is an enlarged fragmentary transverse vertical section on a line corresponding to line 2—2 of Fig. 1 with the amplifier unit in full lines but largely conventionalized.

50 Fig. 3 is an enlarged detail section taken on a line corresponding to line 3—3 of Fig. 4, the parts being shown in their actuated position by dotted lines.

55 Fig. 3A is a fragmentary detail section similar

to Fig. 3, of a modification of the air gap in the magnetic circuit of the pick-up.

Fig. 4 is a fragmentary view in rear elevation of the pick-up assembly.

Fig. 5 is an enlarged detail of the potentiometer control.

Fig. 6 is a circuit diagram of the pick-up potentiometer and amplifier assembly.

Fig. 7 is a fragmentary perspective view of the pick-up assembly.

10 In the embodiment of my invention illustrated by the drawings, the cabinet 1 of the musical instrument 2 is provided with a keyboard 3 having a hinged cover 4 which is adapted to be turned back on the top to afford access to the keys. At 15 the back, the casing is provided with a hinged panel 5 which is adapted to be swung down to afford ready access to the parts for repair and/or adjustment without interfering with the mechanism for initiating the vibration of the reeds. 20

The cabinet 6 containing the audio-frequency amplifier 7 and loud speaker 8 is preferably in the form of a bench table which can be conveniently placed under the main cabinet 1 as illustrated by Figs. 1 and 2 if desired. The loud 25 speaker unit is readily portable and may be positioned according to the acoustic requirements of the room.

30 I may say here for clarity that my musical instrument is substantially noiseless when the amplifier-loud speaker unit is disconnected from the magnetic pick-up or generator associated with the reeds. The vibration of each reed varies the air gap of a magnetic circuit and such vibration is amplified and produces a tone heard from 35 the loud speaker or ear phones or the like.

On the bridge 8, Fig. 3, I dispose a pair of spaced lower bearing rods 9, 9 of magnetic material, the rods being placed near opposite edges of the bridge. On these bearing rods, I mount in spaced parallel relation a series of reeds 10. I dispose upper bearing rods 11, 11 on the reeds directly above the lower bearing rods 9, so that when the bridge-cap 12 is drawn toward the bridge by means of the screws 13, the reeds are 40 clamped firmly in place at spaced points. To hold the upper and lower reed bearing rods in vertical alinement, I provide inner pins 14, 14 and outer lugs 15 and 16, the latter being formed of magnetic material. With the reeds supported 45 in this manner, I provide a central vibratory portion 17 and vibratory ends 18 and 19, the latter projecting beyond the front and rear of the bridge as illustrated.

50 On the wippen support 20, I pivotally connect 55

at 21 a series of wippens 22, there being a wippen for each reed. A felt pad 22' is mounted on the support 20 to noiselessly limit the upward movement of the wippens. The forwardly projecting ends of the wippens are forked and in each fork I mount a striker jack or picker head 23. The pivot of the jack is indicated at 24. The movement of the jack in the wippen is limited by means of felted stops 25, 25 which coat with the ends of the recess 26 at the rear of the jack.

The jack is provided with a curved back surface 27 having a central groove. The jack has upper and lower jaws 28 and 29, and a depending portion 30 carrying the reed striker or picker 31, the latter being hereinafter referred to as a pick for convenience. The pick is secured in place by means of the screw 32 and its normal position or position of rest is below the vibratory end 18 of the reed, the extreme end 18 of the reed being beveled upwardly at 33 for coaction with the pick 31. The pick is made of leather, fiber, celluloid, or wood covered with buckskin or other suitable material. The pick is provided with a slot for the screw so that the pick can be adjusted relative to the reed.

The lower jaw 29 of the pack carries a damper 36 which engages the end 18 of the reed when the parts are in normal position as shown in full lines in Fig. 3. The jack 23 is moved to and held in this position by the coaction of the stop rail 37 with the upper jaw 28, the upper and lower surfaces of the stop rail being felted as illustrated. Each of the striker jacks 23 is provided with a wire spring 38 mounted at its inner end on the wippen support 20. The outer end of the spring is curved upwardly as shown and engages the groove in the curved back 27 of the striker jack lightly so as to provide a slight friction retarding the movement of the jack about its pivot. The spring also coacts with the curved back 27 of the jack providing a slight urge in the direction of movement of the jack from its normal or actuated position. This is illustrated by the full and dotted lines of Fig. 3.

The inner ends 39 of the keys normally rest on the felt 40 and under the wippens 22, there being a key for each wippen. On the inner end of each key, I provide a tappet, suitably a capstan screw 41, for engagement with the wippen, the latter being provided with a felt pad 42 for preventing noise between these parts. Thus, when the key is struck, its inner end is elevated so that the tappet engages and elevates the wippen 22 which in turn elevates the striker jack 23 and brings the pick 31 into engagement with the end 18 of the reed.

Inasmuch as the jack 23 is free to turn on its pivot, the engagement of the pick with the reed end results in the turning of the jack so as to slide the pick out of engagement with the bevel 33 after the pick has slightly elevated the reed. As the jack continues its upward movement, its lower jaw 29 engages the stop rail 37 which turns and holds the jack with its pick in retracted position. With the parts in this position, when the key is released its inner end falls, as does the wippen and striker jack. As the latter falls, the spring 38 holds it in retracted position until the pick is below the plane of the reed whereupon the upper jaw 28 engages the stop rail 37 and swings the jack back to its initial or normal position of rest.

The armature end 19 of each reed is provided with a felted damper 43 having a vertical arm 44 and a horizontal arm 45, the latter being pivotally connected at 46 to the wippen support 20 and hav-

ing an outwardly projecting portion 47 resting on the felted upper surface of the damper lift rail 48. The upward movement of the armature damper 43 is limited by the stop 49, the lower surface of which is felted. The lever 50 is pivotally connected to the bridge 8 at 51 for coaction with the belt 52 near the edge of the inner end 39 of the key. A connecting rod 53 is disposed between the lever 50 and the arm 45 so that when the lever is elevated by the operation of the key, the damper 43 is immediately lifted from the armature end 19 of the reed.

The sustaining pedal is shown at 54, Fig. 1, adjacent the loud pedal 55 and soft pedal 56. The sustaining pedal 54 is connected to the damper lift rail 48 by means of the tappet 57 which is adapted to engage the felted lower surface of the damper lift rail 48 to raise the same and all of the armature dampers 43 when the pedal 54 is depressed. The damper lift rail 48 is carried by the arms 58 at the ends of the rockshaft 59 which is pivotally connected to the back 60 of the cabinet as illustrated by Figs. 2 and 3. The damper lift rail 48 is held down in engagement with the upper end of the tappet 57 by means of the spring 61, Fig. 2.

The generator or pick-up includes a plurality of pole pieces 62 constituting cores for the coil windings 63, the pole pieces being carried for vertical adjustment by means of the magnetic pole piece holders or brackets 64 mounted on the bottom of the bridge 8. On the tops of the pole pieces 62, I mount pole faces 65 in spaced relation to the armature ends 19 of the reeds, there being in the embodiment illustrated a pole face associated with each three reeds. Permanent magnets 66 are mounted on the back of the bridge 8 with their upper poles connected to the rear lugs or pole pieces 16, the latter being in turn electrically connected to the magnetic bearing rods 9 and 11. In this case, the rear bearing rods 9 and 11 constitute upper bus bars. The lower poles of the magnets are connected to the magnetic pole piece holders 64 by means of lower bus bars 67. As illustrated by Fig. 3, each magnet 66 is held in place by means of a clamp piece 68 and a screw 69, the screw being threaded into the rear of the bridge 8 as illustrated. In the embodiment illustrated, I provide a magnet for each three pole pieces 62.

As illustrated by Fig. 6, the coil windings 63 are connected in parallel circuit relation with the input of the audio-frequency amplifier 7, there being a potentiometer 70 having a variable contact 71 in the circuit between the pick-up and the amplifier. The variable contact 71 is controlled by means of a central pinion or gear 72 and a pair of racks 73 and 74 meshing with the gear at opposite sides thereof, the movement of the racks being guided by the casing 75. The rack 73 is associated with the loud pedal 55, while the rack 74 is associated with the soft pedal 56. Thus, when pedal 56 is pressed down, the rack 74 turns the pinion gear 72 so as to move the variable contact 71 to decrease the volume of the loud speaker accordingly. At the same time, the pinion gear moves the rack 74 down and the pedal 56 up. When the pedal 55 is depressed, rack 73 is elevated and turns the pinion gear and the potentiometer contact 71 to increase the volume of the loud speaker accordingly. At the same time, the pedal 56 is elevated. Thus, the instrument can be set for any volume up to the capacity of the amplifier-loud speaker unit and will remain so until changed by the player by 75

manipulating the pedals. An instant change in volume is possible before or after a key is struck and any degree of volume can be obtained and maintained without the player holding the pedals in place.

In the operation of my instrument, as the outer end of the key is struck by the player, the inner end 39 of the key rises. After the inner end 39 of the key has traveled far enough to close the gap between its tappet 41 and the wippen 22, the key lifts the wippen which swings upwardly on its pivot 21. The damper 43 is lifted and at once releases the armature 19, the damper 36 is lifted from the inner end 18 of the reed 10, and the pick 31 contacts the reed end 18 causing the latter to vibrate as the pick slips off the end 33 thereof. Striker jack 23 oscillates freely on its pivot 24.

At the instant the pick 31 vibrates the reed end 18, the striker jack 23 is out of contact with the stop rail 37 and free to oscillate in either direction on its pivot so that the contact of the pick 31 with the reed end 18 is to the right of the perpendicular through pivot 24. The reed end 18 acts on the pick to oscillate the striker jack 23 in a direction which moves the pick away from the reed end 18. Because at the instant of contact of the pick with the reed end the striker jack is free to oscillate, a hard stroke on the key 39 which throws the striker jack and pick upward with great speed will vibrate the reed vigorously and give a loud tone. A gentle stroke on the key will throw the striker jack and pick upward with less speed, allowing the striker jack time to oscillate and draw the pick back from contact with the reed end 18 before the pick has entirely lifted past the reed end, and a weaker vibration of the reed results, and consequently a weaker tone. Thus by varying the force with which the key is struck by the player, any degree of tone intensity can be obtained.

Inasmuch as the operation of my action mechanism is an important feature of the present invention, it is described in detail as follows. Referring to Fig. 3, when the key 39 lifts the wippen 22, the jack 23 is lifted therewith. When the jack has lifted far enough so that the pick 31 is in contact with the inner end 18 of reed 10, neither the upper jaw 28 nor the lower jaw 29 of the jack is in contact with the stop rail 37. Thus, the jack 23 is free to oscillate in either direction. Since the end of the pick is either under the pivot 24 of the jack or in front of it, the pressure of the extreme end of the reed on the pick causes the jack to oscillate to move the pick out from under the end of the reed. It will also be observed that as the jack oscillates in such direction, the pick drops farther below the end of the reed. The extent of this drop is slight and the speed with which it develops is not materially affected by the speed with which the pick engages the reed.

However, at the instant of contact between the pick and the end of the reed, a slight amount of friction is developed between these parts, which is sufficient to tend to hold them together. If the jack and wippen are elevated rapidly by a hard blow on the key, the pick is forced against the reed before the oscillation of the jack draws the pick down and out from under the end of the reed. The friction between the pick and reed increase more rapidly than the rapidity with which the pick falls away from the reed and so assists the pick to lift the reed higher and

vibrate it through a wider arc before the pick can slip out from under the end of the reed.

On the other hand, if the key 39 is struck gently, the wippen 22 and the jack 23 are elevated more slowly and the speed with which the pick falls away from the reed and oscillates back away from the same is also less because the pick does not come against the reed with so much force, but the speed of the pick falling away from the reed and out from under the same decreases much less than the speed with which the jack lifts and the pick travels upwardly past the line of the reed. The friction between the pick and reed consequently develops more slowly and does not tend to hold the pick against the reed and prevent it from oscillating back therefrom. On the contrary, the pressure of the reed against the pick causes the pick to move away from the end of the reed and at the same time oscillate out from under the same before the pick has lifted past the end of the reed. Consequently, the pick does not lift the end of the reed so far out of line in order to get by and the reed is not vibrated as widely.

The above action is so definite that with full amplification of the vibration pattern of the reed turned on, a gentle stroke of the key will cause the pick to brush the reed so lightly that the amplified tone is barely audible. A vigorous stroke of the key causes the pick to vibrate the reed so widely that the resultant audibility of the tone can be up to the capacity of the amplification-speaker system. A very gradual press of the key will brush the pick past the end of the reed without vibrating the latter at all. This is because the jack is free to oscillate the pick away from the reed when the pick touches the end of the reed. The only resistance to this movement is the inertia of the jack itself, and as it is pivoted in the middle such inertia is so slight that the jack can be moved with the breath after the wippen has lifted the upper jaw of the jack off of the stop rail. The friction between the spring 38 and the groove in the back of the jack is also very slight. At the time the pick contacts the end of the reed, the spring 38 has traveled forwardly and is over the pivot 24 so that it has no tendency to urge the pick either forwardly or backwardly, the slight friction between the spring and groove tending to hold the pick in place.

When the reed has forced the pick and jack to oscillate clear of the end of the reed, the spring presses slightly on the jack ahead of its pivot and tends to hold it there. At the same time, the lower jaw 29 engages the stop rail 37 and holds the jack in fixed position with the pick clear of the reed. When the key is released, the wippen drops with the jack until the pick is below the line of the reed, whereupon the upper jaw 28 engages the rail 37 and oscillates the jack to its normal position with the pick under the end of the reed. The edges of both the pick and reed are beveled so that when the pick starts to slip off the end of the reed it does so freely and without interference. Further, the reed cannot start to vibrate without its end lifting and making it easier for the pick to slip off.

The wippen 22 and its striker jack 23 are thrown back or retracted by the pressure of the reed end 18 against the pick 31, so that the pick will clear the reed end. The striker jack and pick are fully retracted and held in this position by the contact of the lower jaw 29 with the stop rail 37. The spring 38 by a slight pressure in the

groove in the curved back 27 of the striker jack assists in holding the striker jack in retracted position with the pick well away from the reed end and prevents any dancing back and forth 5 of the jack against the felt on the stop rail 37 when the key is struck vigorously. As long as the lower jaw 29 is in contact with the stop rail 37, the pick 31 cannot move toward the reed end 18 and get on top of it or strike the end of it. The 10 pressure of the tappet 41 against the wippen 22 holds the striker jack 23 in such position as long as the key is held down.

When the key is released and its inner end 39 drops back on the felt pad 40, wippen 22 drops 15 with it. When the wippen drops far enough so that the pick is beneath the plane of the reed 10, the upper jaw 28 of the striker jack 23 engages the stop rail 37 and oscillates the striker jack on its pivot 24 so that the pick is returned to its 20 normal or rest position under the reed end 18 ready for another stroke. The gap between the tappet 41 and the wippen 22 is such that when the key has returned approximately one-third 25 of the way to its position of rest, the pick is in its normal position under the reed end 18. This is a very important feature of my invention inasmuch as it provides for an extremely rapid repetition of tones from the reed by the operation of the key. Tones can be repeated by consecutive 30 blows on the key that are so close together that the key has time only to return one-third of the way to its position of rest. A distinct repetition of tones is possible as rapidly as the key can be struck.

35 The spring 38 being mounted on the rail 20 does not rise with the striker jack 23, but its point of contact with the curved back 27 of the jack moves forward relative to pivot 24 and presses lightly thereon. The spring does not pass the 40 perpendicular of the pivot 24 until after the reed end 18 has been vibrated by the pick 31. The pressure of the spring in the groove at the back of the jack assists in holding the jack in its retracted position. When the key is released and 45 the wippen, jack and pick returned to their normal position, the spring contact moves back to the other side of the perpendicular of the pivot, and after the pick is beneath the reed end, the spring presses on the jack and assists the stop 50 rail 37 in holding the jack with the pick in position under the reed end without any further oscillating or vibrating of the jack on its pivot.

The armature end 19 of the reed 10 is tuned to the desired pitch, this being controlled by the 55 length, weight and elasticity of the reed. A reed is provided for each note of the scale. To cause the reed to vibrate freely and sustain the vibratory activity for a substantial length of time, the reed is held with great firmness, also the bearing rods 9 and 11 which grip or clamp the reed are perfectly aligned so that the reed is contacted thereby both above and below at exactly the same distance from its free ends. The bearing rods 9 and 11 are vertically aligned so that their centers 60 are perpendicular to the reed 10. This alignment is maintained by the pins 14 and lugs 15 and 16, the distance between the pins and lugs being exactly equal to the thickness of the bearing rods.

70 The central portion of the reed between the bearing rods is free. This portion 17 of the reed is short enough so that the natural frequency thereof is a great deal higher than the highest note of the keyboard. If the end 18 of the reed 75 is tuned exactly with the end 19 thereof, the

vibration of end 18 will vibrate the central portion 17 of the reed which will in turn vibrate the end 19, the frequency of the vibration of the end 19 being the same as that induced in the central portion 17 of the reed. Thus, the vibration of the end 18 can be stopped after the end 19 has started and end 19 will continue vibrating for its natural vibratory period. If the ends 18 and 19 are both permitted to vibrate freely, they reinforce each other and vibrate longer than 10 either would alone.

If reed end 18 is slightly above or below the end 19 in frequency, the vibration of the end 18 will still start the end 19 to vibrating, but the ends act to periodically reinforce and damp each other, 15 making a beat or vibrato in the tone. This vibrato to be acceptable musically must be always of a frequency that permits the ends 18 and 19 to be near enough the same pitch for the vibration of the end 18 to start the end 19 vibrating 20 instantly. At the instant the pick 31 vibrates reed end 18, dampers 36 and 43 have freed the ends 18 and 19 for vibration. As long as the key is held down, the dampers are held in elevated position above the reed ends. When the key is 25 released, the dampers drop and instantly stop the reed ends from vibrating. If the reeds are tuned for vibrato, as long as a key is held down a vibrato is produced. If damper 43 is held from the reed end 19 by the pedal 54 through tappet 30 57 and the damper lift rail 48 and the key is released as soon as it is struck, the reed end 19 will be vibrated by the end 18, but immediately damper 36 will stop the vibration of the reed end 18. The end 19, however, will continue to vibrate 35 until the damper 43 is dropped, but the tone produced is smooth and without vibrato. Thus, the player can use the vibrato or not as the music to be played may require.

The reed end 19, lug 16, bearing rods 9 and 11, 40 magnet 66, pole holder 64, lower bus bar 67, pole piece 62, and pole face 65 comprise the magnetic circuit. An air gap is provided in this circuit between the reed end 19 and the pole face 65. As the reed end 19 vibrates, this air gap is varied in 45 the exact pattern of the string vibration. This variation causes a corresponding variation in the magnetic flux line in the core of the coil winding 63 which induces in the coil winding an alternating current of the same pattern as the vibration 50 of the reed end 19. Such alternating current is amplified by the audio-frequency amplifier 7 and converted into sound pressure waves in the air by the loud speaker 8 connected to the output stage 55 of the amplifier.

It is only the frequency pattern of reed end 19 that is represented in the current induced in the coil winding 63. Thus, the impact noise of the pick 31 on reed end 18, the impact noise of damper 36 on reed end 18 and mechanical noises in general are not included in the tone heard from the speaker.

My structure of the magnetic circuit offers convenient means for producing musical tones of extremely high frequency. By changing the relative positions of reed end 19 and the pole face 65, as illustrated by Fig. 3A, one complete cycle of reed end 19 produces two complete cycles of flux variation and induced current in the coil winding 63. Thus, the resulting tone emanating from the loud speaker is one octave higher in pitch than the frequency of vibration of the reed end 19.

This is made possible because the reed end 19 completes one cycle when it moves from its highest position to its lowest position and back to its

5

highest position again. In completing one-half of such cycle, that is to say, in moving from its highest position to its lowest position, the end of the reed varies the flux path between the reed 5 end and the pole face 65 in such a way that one complete cycle of alternating current is induced in the coil winding 63. In its return from its lowest position to its highest position, the end of the reed varies the flux path in such a way as to induce another complete cycle of alternating current in the coil winding. For each complete vibration of the reed, two complete cycles of alternating current are produced. Thus, if the reed 10 is tuned to produce 2000 complete vibrations or 15 cycles per second, there will be 4000 cycles per second in the alternating current induced in the coil and the tone emanating from the loud speaker is one octave higher than that emanating from the reed itself.

20 It is well known that a self sustaining vibrator loses its ability to sustain tones as the frequency of its vibration is raised. Thus, the extremely high tones of the conventional piano above two thousand cycles have very little or no sustaining power. By means of my arrangement, as illustrated by Fig. 3A, the vibratory life of octave-lower frequencies can be applied to such high frequency vibrators. I have produced tones in this manner an octave higher than the highest tone 25 of the usual piano keyboard, which tones are sustained for several seconds.

30 The output of the magneto-electric circuit is of sufficient strength to operate a set of head phones without the aid of an amplifier. Thus, the instrument can be used for practice with only the player hearing it through head phones (not shown). Any number of the instruments can be used simultaneously in this way in the same room without interference. As pointed out above, the 35 tone from the reeds without head phones or an amplifier-speaker unit is practically inaudible.

40 From the above description, it will be apparent to those skilled in the art that I provide a plucking or picking action that is (1) economical in cost, (2) light in weight, (3) simple in construction, (4) of the same touch as a piano, (5) will not allow the pick to catch on the reed or on a string (not shown) as it plucks it, (6) of as rapid repetition as a first class grand piano, (7) simple 45 to adjust, (8) adaptable to pluck any type of string (not shown) or reed, (9) positively able to furnish the player with means to control the intensity of the tone by the force with which the key is struck, and (10) able through novel means 50 to pluck the reed with the striker as it moves upwardly and miss the reed as it returns the striker to its position thereunder.

55 My keyboard instrument is very light in weight, relatively small, and economical to manufacture. It contains a series of tuned vibrators covering all the scale frequencies playable by means of a keyboard. While the tone from the vibrators is practically inaudible, such tone may be amplified by a suitable audio-frequency amplifier and loud speaker to any desired volume. The instrument is adapted to produce a vibrato that can be used or not at the discretion of the player. The magnetic circuit is capable of including up to ninety-six tuned reeds with as few as seven small permanent magnets furnishing all of the magnetic flux necessary for practical operation. It should be noted here that while I prefer to use permanent magnets, electro-magnets may be used if desired.

60 The player can damp the free end of the reed

that is plucked without interfering with the vibration of the free end not plucked but vibrated sympathetically by the plucked end. The magneto-electric structure is so assembled in my instrument that it is in proper relation to the vibratory reeds and is accessible for adjustment without disturbing them, the picking action, or the damper or dampers. My arrangement provides a dual pedal operated volume control constituting a loud and soft pedal, the operation of either of which reverses the other. The result is a deeply resonant, sonorous and organ-like tone capable of perfect blending because of its freedom from overtones and partials, and peculiarly moving and beautiful. A perfectly even 15 scale is produced with every tone developed to its maximum of quality.

16 I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Having thus described my invention what I 20 claim as new and desire to secure by Letters Patent is:

1. A musical instrument comprising a series of reeds, a wippen support, a series of wippens pivotally connected to said support, a striker jack pivoted to each wippen and having a curved back, upper and lower jaws and a depending pick carrier, a damper on the lower jaw resting normally on the end of the reed, a reed pick on said pick carrier normally positioned below said reed for first engaging and then sliding off of the front end of the reed as the wippen is elevated, a stop rail disposed between the upper and lower jaws of said striker jacks for coaction with the lower jaws to hold the striker jacks in retracted position, a 40 series of wire springs mounted on said wippen support for frictional coaction with the curved backs of said striker jacks, and a series of keys having their inner ends positioned under said wippens for elevating the same when struck.

2. A musical instrument comprising a series of reeds, a wippen support, a series of wippens pivotally connected to said support, a striker jack pivoted to each wippen and having a curved back, upper and lower jaws and a depending pick carrier, a damper on the lower jaw for resting normally on the end of the reed, a reed pick on said pick carrier normally positioned below said reed for first engaging and then sliding off of the front end of the reed as the wippen is elevated, a stop rail disposed between the upper and lower jaws of said striker jacks for coaction with the upper jaws to hold the striker jacks in normal position and for coaction with the lower jaws to hold the striker jacks in retracted position, and means for frictional coaction with the curved backs of said striker jacks.

3. A musical instrument comprising a series of reeds, a wippen support, a series of wippens pivotally connected to said support, a picker jack pivoted to each wippen and having a curved back, upper and lower jaws and a depending pick carrier, a damper on the lower jaw for resting normally on the reed, a reed pick on said pick carrier normally positioned below said reed for first engaging and then sliding off of the reed as the wippen is elevated, a stop rail disposed between the upper and lower jaws of said striker jacks for coaction with the upper jaws to hold the striker jacks in normal position and

for coaction with the lower jaws to hold the striker jacks in retracted position, a series of springs mounted on said wippen support for coaction with the curved backs of said striker jacks 5 to urge said wippens to normal position, and a series of keys having their inner ends positioned under said wippens for elevating the same when struck.

4. A musical instrument comprising a bridge, 10 a pair of lower bearing rods disposed on said bridge near the opposite edges thereof, a series of spaced parallel reeds arranged on said lower bearing rods and having overhanging ends, a pair of upper bearing rods disposed on said 15 reeds directly above said lower bearing rods, a bridge-cap mounted on said upper bearing rods and connected to said bridge, vertical pins arranged between said bridge and bridge-cap and engaging the inner sides of said bearing rods, 20 and vertical lugs mounted on the front and back faces of said bridge and bridge-cap and engaging the outer sides of said bearing rods.

5. A musical instrument comprising a series 25 of pivotally mounted wippens, a series of keys operatively associated with said wippens, a picker jack pivotally mounted on each wippen and provided with spaced jaws, a reed pick on each jack, a damper on each jack normally resting on the associated reed, a spring friction means for the 30 jack, and a fixed stop positioned to alternately coat with the jaws of the jack when the wippen is at the ends of its stroke, the jack being free of said stop when in its reed engaging position.

35 6. A musical instrument comprising a series of pivotally mounted wippens, a series of keys operatively associated with said wippens, a picker jack pivotally mounted on each wippen and provided with spaced jaws, a reed pick on each jack, 40 and a fixed stop positioned to alternately coat

with the jaws of the jack when the wippen is at the ends of its stroke, the jack being free of said stop when in its reed engaging position.

7. A musical instrument comprising a series 5 of pivotally mounted wippens, a series of keys operatively associated with said wippens, a picker jack pivotally mounted on each wippen and provided with spaced jaws, a reed pick on each jack, a damper on each jack normally resting on the associated reed, and a fixed stop positioned to alternately coat with the jaws of the jack when the wippen is at the ends of its stroke, the jack being free of said stop when in its reed engaging position.

8. A musical instrument comprising a series 15 of pivotally mounted wippens, a series of keys operatively associated with said wippens, a picker jack pivotally mounted on each wippen and provided with spaced jaws, a reed pick on each jack, and a fixed stop positioned to alternately coat 20 with the jaws of the jack when the wippen is at the ends of its stroke, the jack being free of said stop when in its reed engaging position.

9. A musical instrument comprising a bridge 25 and coacting cap piece, a series of spaced magnetic reeds arranged between said bridge and cap piece, and pairs of spaced clamping bars between which said reeds are disposed and supporting the reeds to provide vibratable ends and a vibratable intermediate portion between the 30 bars.

10. A musical instrument comprising a series 35 of spaced magnetic reeds arranged between said bridge and cap piece, and pairs of spaced clamping bars between which said reeds are disposed and supporting the reeds to provide vibratable ends and a vibratable intermediate portion between the bars.
